UNITED STATES PATENT OFFICE.

FRED F. MAIN, OF COLUMBUS, OHIO, ASSIGNOR TO MAIN RETURN COMPANY, OF CLEVELAND, OHIO, A CORPORATION OF OHIO.

AUTOMATIC WRITING-MACHINE.

1,034,131.

Specification of Letters Patent. Patented July 30, 1912.

Application filed July 3, 1907. Serial No. 382,110.

To all whom it may concern:

Be it known that I, FRED F. MAIN, a citizen of the United States, residing at 1486 Pennsylvania avenue, Columbus, in the 5 county of Franklin and State of Ohio, have invented certain new and useful Improvements in Automatic Writing-Machines, of which the following is a specification.

My invention relates to certain new and 10 useful improvements in self acting or automatic writing machines and similar key instruments, and it has for its object to produce by improved automatic mechanical devices, the exact results now secured by manual means. This object is attained by the 15 mechanism illustrated in the accompanying drawings in which like characters of reference denote similar parts throughout the several views in which:—

20 Figure 1, is a side elevation partly in section showing the invention applied to a writing machine. Fig. 2, is a fragmentary perspective showing one form of trackerboard with contact wheel, Fig. 3, is a modification of Fig. 1, and Fig. 4, is a side elevation of the shifting gear.

In the drawings 1, designates the keys of a typewriter to which cords 2, are connected, the latter carrying iron cores which are 30 suspended by means of coil springs 4, secured at one end to said cores and at their other ends to a suitable support 5. There is provided a cord and above related parts for each key, each core working within a 35 solenoid 6. Each of the solenoids is included in an electrical circuit which embodies wire 7, leading to a battery 8, and thence to contact wheel 9, the latter adapted to bear against the contact roll 10, of the tracker- 40 board mechanism, roll 10, being connected to solenoid 6, by wire 11. Each contact wheel 9, is mounted on one end of a centrally pivoted lever 12, which has a coil spring 13, connected to its opposite end.

45 14, designates the usual perforated sheet well known in the art of self-playing musical instruments. This sheet keeps the individual contact wheels 9, free of contact with roll 10, until at such times as perforations in the 50 sheet allows one of the spring pressed wheels 9, to come into contact with common roll 10, when the corresponding solenoid will be energized causing a sudden pull of its core into the helix which extends the spring and 55 gains momentum until the slack is taken

from the cord 2, when the key 1, is given a sharp jerk which produces a snappy movement required to give desirable printing results. As shown in Fig. 3, I also contemplate the use of a double trackerboard. 60 Around one roll 15, passes the sheet carrying the perforations for the addresses or headings of the letters to be written, while the other roll 16, carries the sheet formed with the perforations for the letter. In this 65 form there are two contact wheels 17, 18, each borne at the ends of a head 19, carried by a spring pressed rod 20, sliding in a guiding sleeve 21.

Fig. 4, shows gears 21, 22, with shift gear 23, which actuates the rolls 15, and 16, alternately to print the addresses and letters. If desired these gears may be directly mounted upon the contact rolls or they may be geared thereto in any manner. The movement of this shift gear is controlled by additional keys and solenoids with the usual members in the trackerboard. In actual work the addresses are reproduced in the perforated sheet, while the letter is reproduced in a separate sheet, all shown in Fig. 3. These sheets are then placed upon their respective rolls in the trackerboard, and gear 23, being shifted, the address roll is revolved carrying the address sheet through 85 the trackerboard which by reason of its perforations causes the various keys to print each in its order, and exactly as though by manual operation. When the address is complete the shift perforation throws gear 90 23, to the opposite feed roll when the letter sheet is caused to pass through the trackerboard and its characters are similarly produced.

In Fig. 3, it will be noted that each roll 95 15, 16, is in circuit with a solenoid by means of wire 24, and wire 25, which connects the latter and has its ends leading to said rolls 15, and 16. Likewise each wheel 17, 18, is in circuit with said solenoid by means of wire 26, and wire 27. Furthermore it will be noted that the machine may be placed in one room and the trackerboard in another. Again several machines may be connected to the trackerboard so that a plurality may be operated from one trackerboard. For regular work the machines are connected in pairs, one printing the envelop and the other the heading, the envelop printing machine rests during the writing of the body 110

of the letter. It will furthermore be observed that by the rotation of the tracker-board the fusing of the contact fingers therewith is prevented, this difficulty frequently arising from stoppage. Hitherto this fusing has continued, in many cases, until the fingers and the roll were separated by the edge of a perforation whereby the sheets were often torn. By having the contact rolls 10 serve as the driving rolls, the members are positively separated before the edge of a perforation can be reached.

Having thus fully described my invention what I claim as new and desire to secure by 15 Letters Patent is:—

1. In combination with a typewriting machine and the key bars thereof, a common contact roll, a perforated sheet engaging over said roll, a centrally pivoted lever for each 20 key bar, a rotatable wheel on one end of each lever engaging said contact roll, a spring connected to the opposite end of each lever, a solenoid for each key bar, a core working in each solenoid, a spring connected 25 to each core and to a suitable stationary point so as to resiliently support each core, a connection between each core and the free end of each of said key bars, and an electrical circuit including the solenoids, 30 said common roll and the rotatable wheels of said levers.
2. In combination with the key bar of a typewriter machine, a solenoid for each key bar, a core for each solenoid, a coil spring 35 for each core connected at one end to said core and at its opposite end to a suitable stationary point, a connection between each core and key bar, and means to energize each solenoid.
- 40 3. In combination with a writing machine, a pair of rolls each driving a perforated sheet passing thereover and serving as contact rolls, one of said sheets being for the purpose of effecting printing of the

envelops and the other sheet being for the 45 purpose of effecting printing of letters, a gear wheel for rotating each roll, said gear wheels being arranged in spaced relation, and a shiftable gear disposed in said space between said gears to operate either while 50 the other remains quiescent.

4. In combination with a writing machine, a pair of rolls each driving a perforated sheet passing thereover and serving as contact rolls, one of said sheets being for 55 the purpose of effecting printing of the envelopes and the other sheet being for the purpose of effecting printing of letters, and means normally operated to have rotary movement for rotating each of said rolls, 60 said means being shiftable from one roll to the other to cause actuation of one while the other remains quiescent.

5. An automatic recording machine comprising keys, electrically operated means 65 for operating said keys, a roll for driving a master sheet, and in circuit with said means, and spring controlled fingers contacting with the roll through the perforation in the master sheet to close the circuit 70 to operate said means.

6. An automatic recording machine comprising keys, solenoids having their cores connected by slack wires to said keys and energized by circuit closing means operated by a master sheet, and spring supports for carrying said cores independent of said keys, whereby the pull of the core is effective at the last instant of its travel.

7. An automatic recording machine, comprising keys, solenoid magnets, means for connecting said keys to the cores of said magnets, and yieldable means for normally relieving the keys of the weight of said core.
